UNITED STATES PATENT OFFICE

2,439,767

ELECTRICAL CONNECTOR

Hugo H. Wermine, Wheaton, Ill., assignor to
 Belden Manufacturing Company, a corporation
 of Illinois

Application March 20, 1943, Serial No. 479,846

10 Claims. (Cl. 173—361)

1

The present invention relates generally to electrical connector plugs of the type used for connecting appliance cords or the like to a source of electrical power, and it has particular relation to the blade terminals which form a part of such devices. This application is a continuation in part of my prior application Ser. No. 375,870, which was filed on January 25, 1941, now abandoned, and which is assigned to the assignee of this invention.

The usual electrical connector plug of the subject type comprises a body of insulating material, having a central aperture for receiving the conductor cord, and two or more blade terminals for the cord conductors. The terminals are supported upon, and project outwardly from, the insulating body and are adapted to engage the contacts of the receptacle or other power outlet with which the plug is to be used. For safety reasons, it is desirable that the plug body shall be made of a soft, unbreakable material such as a resilient rubber compound, although a large number of the connector plugs in use are of the so-called hard body or breakable type.

Considerable difficulty has been experienced in the past in providing good electrical contact between the blade terminals of connector plugs and the cooperating contacts of receptacles or other power outlets, particularly in the case of receptacles which have been in use for some time. To overcome this difficulty, it has been proposed to use spring blades as the plug terminals, but despite considerable work along this line and the development of a substantial number of devices no completely satisfactory spring blade has been developed.

The principal object of the present invention, therefor, is to provide an improved spring blade for electrical connector plugs, and the like, which shall assure good electrical contact with the contacts of standard receptacles or other power outlets regardless of wearing or loss of resilience in those contacts, and which shall be free from the other objections of the prior devices.

As will hereinafter appear, this object is accomplished by the provision of a transversely resilient, two-ply blade of novel structural arrangement and design, the shape of the blade being such that it not only accomplishes improved electrical contact with the contacts of standard receptacles but, in addition, it provides a mechanical connection between the associated plug body and the receptacle. This mechanical connection between the plug body and the receptacle is a substantial departure from the teachings of the prior

2

art, and is an important feature of my invention, for the reason that it prevents overstressing both of the terminal blades and of the cooperating receptacle contacts. The spring blades of the present invention may be used in connection with either hard or soft body plugs.

It is also an object of my invention to provide an improved spring blade which shall include means for anchoring the blade in place 10 in the supporting body with which it is used, and to provide an improved spring blade in accordance with the aforementioned objects which can be manufactured at low cost by the use of conventional metal working equipment.

15 Other objects and the various advantages of the invention will be made apparent by reference to the accompanying drawings and the following description of certain preferred embodiments thereof.

20 In the drawings:

Fig. 1 is a perspective view, partially in section, of a soft body, connector plug provided with spring blades constructed in accordance with the present invention;

25 Fig. 2 is a vertical sectional view of the connector plug shown in Fig. 1;

Fig. 3 is a sectional view showing the manner in which the plug illustrated in Figs. 1 and 2 is inserted into a receptacle, the blades being illustrated in elevation and pushed about two-thirds of the way into the receptacle in this view;

30 Fig. 4 is a view similar to Fig. 3 showing the plug in its normal operating position with the blades completely seated in the receptacle, the blades being illustrated in section in this view;

Figs. 5 and 6 are elevational views partly in section showing the manner in which the spring blades of the present invention coact with various types of standard outlet receptacles;

35 Fig. 7 is an elevational view of one of the blades forming a part of the connector plugs illustrated in Figs. 1 to 4;

Figs. 8 and 9 are enlarged sectional views on 40 the lines 8—8 and 9—9, respectively, of Fig. 7;

Fig. 10 is a perspective view, similar to Fig. 1, showing a modified form of the invention;

Fig. 11 is a vertical sectional view of the plug 45 illustrated in Fig. 10, one of the blades being illustrated in section and the other in elevation;

Fig. 12 is an elevational view of one of the blades forming a part of the plug illustrated in Figs. 10 and 11;

Fig. 13 is a vertical section of the blade illustrated in Fig. 12;

Fig. 14 is an enlarged sectional view on the line 14—14 of Fig. 13;

Figs. 15 and 16 are, respectively, front and side elevational views of a second modified blade construction embodying certain of the features of the present invention;

Fig. 17 is a vertical sectional view of the blade illustrated in Figs. 15 and 16;

Fig. 18 is an enlarged sectional view on the line 18—18 of Fig. 17;

Figs. 19 and 20 are, respectively, front and side elevational views of another blade construction in accordance with the present invention;

Fig. 21 is a side elevational view of a slightly modified form of the blade construction illustrated in Figs. 19 and 20;

Figs. 22 and 23 are, respectively, enlarged sectional views on the lines 22—22 and 23—23 of Figs. 20 and 21;

Fig. 24 is a vertical sectional view similar to Fig. 2 of a plug equipped with spring blades of the types shown in Figs. 19 to 23;

Fig. 25 is a front elevational view of another spring blade construction embodying certain of the features of the present invention;

Fig. 26 is a sectional view on the line 26—26 of Fig. 25; and

Figs. 27 and 28 are, respectively, front and side elevational views of still another spring blade construction embodying certain of the features of the present invention.

The connector plugs illustrated in the drawings are of the soft body, two conductor type, and are similar in construction to the connector plugs illustrated in my earlier Patent 1,858,196. These plugs include a main body part 31 which is preferably molded of a resilient, rubber or equivalent compound. The main body part 31 is provided with a centrally disposed passageway 33 for receiving a connector cord 35, which in the structures illustrated is of the duplex type, and with two suitably positioned recesses 37 for receiving and tightly engaging the inner or shank end of the two terminal blades. In the construction shown in Figs. 1 to 4, the recesses are enlarged at the inner portion thereof so as to provide an abutment 38 which, as will hereinafter appear, coacts with the blades to lock them in place.

The upper portion of the central passageway 33 is enlarged to receive a secondary body part or retainer 39 which serves to hold the blades in spaced relationship and to aid in supporting them in the main body part 31. In order to hold together the plug parts without the use of screw or other fastening means, in accordance with the disclosure of Patent 1,858,196, the walls of the main or outer body part 31 are provided with two diametrically opposite, under-cut portions 41 (see Figs. 1 and 10) which engage projecting edge portions 43 of the secondary or inner body part 39 when the plug is assembled. The plug parts are thus held together by the resilience of either or both of the body parts, and the plugs can be assembled only by virtue of the fact that at least one of the body parts is made of resilient material. Each of the conductor cords 35 includes two, separate, insulated wires or cables 45, and the end of one of the metallic conductors forming a part of each of the wires 45 is soldered or otherwise attached to one of the blades as illustrated at 47. The outer body part 31 is recessed as illustrated at 49 to receive the solder or other connecting means.

During the assembling of connector plugs of the general type illustrated in the drawings, the

outer body part 31 is slipped over the end of the connector cord with which the plug is to be used, and the connector blades are soldered in place on the bared ends of the cord conductors. The outer body part 31 and the cord are then placed in the stationary element of an assembly press. The movable element of this press is adapted to hold the blades in parallel relationship with one of the inner body parts 39 in place therebetween. On operation of the press, the blades are automatically pressed into and seated in the blade supporting recesses 37, and the inner body part 39 is forced into place so as to lock with the outer body part 31 as shown. The plugs may be assembled by hand in a similar manner.

As stated previously, the present invention is concerned primarily with the terminal contacts or blades, and, as will hereinafter appear, the spring blades of my invention can be used in connection with resilient or soft body plugs, such as have been described above, or in connection with hard body plugs. In view of the fact that all power outlet receptacles are made to certain standard dimensions, blades for use with electrical plug connectors must conform to standard dimensional requirements, and this requirement seriously complicates the problem of providing a satisfactory spring blade, particularly since these dimension requirements were decided upon long before the need for spring blades arose.

The standard specifications in use in the United States at the present time are those of the Underwriters Laboratory, which is sponsored by the National Board of Fire Underwriters. The specifications of the Underwriters Laboratory provide that the blade shall project from the plug body not less than .625 inch and not more than .718 inch, and that if the blade be provided with a hole adjacent its outer end, such hole shall have an inside diameter of .056 to .125 inch and shall be located so that the outermost edge of the hole is .542 inch, with certain allowable tolerances, from the face of the plug body. The term "face of the plug body" is applied to the plane of contact between the plug and the cooperating receptacle, and is used in this sense herein. The Underwriters specifications further provide that the width of the blade shall be .250 inch, that the incompressible thickness of the blade shall be not more than .060 inch, or approximately $\frac{1}{16}$ of an inch, and that the center lines of the blades in the completed plug shall be spaced apart exactly .50 inch.

The Underwriters specifications include similar provision for the receptacles with which the plugs are used. While the receptacle specifications permit of somewhat greater variation than the plug specifications, they do provide for a blade receiving opening in the receptacle having a minimum thickness within the range of approximately $\frac{1}{16}$ to $\frac{3}{16}$ of an inch, and a spacing on the center lines of the receptacle openings of exactly one-half inch, the spacing of the socket openings thus coinciding with the standard spacing of the blades. The shape of the insulating body part of so-called "standard" receptacles varies quite substantially. The receptacle body parts 51 and 53 of Figs. 5 and 6 are illustrative of two extreme types, the body part 51 of Fig. 5 having a body which is flush with the plug face, and the body part 53 of Fig. 6 being of the deeply recessed type. A more common type is illustrated at 55 in Figs. 3 and 4.

The improved spring blade of the present invention constitutes a two-ply, transversely re-

silent blade which, in its physical dimensions, fully conforms to the above stated requirements of the Underwriters Laboratory. The blade is manufactured by folding over and shaping a strip of suitable spring material of standard prong width (.25 in.) so as to provide two longitudinally spaced, transversely resilient contact portions, A and B, and a shank or support portion S, which may take various forms.

The outermost contact portion A comprises co-extensive, substantially parallel sections 57 of the strip which are spaced apart a distance which should not exceed about one-fourth the width W of the strip and which have a length within the approximate range of W to three halves W. In certain instances, it has been found desirable to provide a slight taper of the order of about 2 to 5 degrees to the two half sections 57 of the contact portion A, the taper being in such direction as to provide the minimum blade width at the outer extremity of the blade. Hence, the term "substantially parallel" as used herein is intended to include constructions which may be slightly tapering, or which are truly parallel.

The inner contact portion B has a length approximately equal to three halves the width W of the strip, and comprises symmetrical, outwardly bowed, arcuate sections 59 of the strip, the radius of the defining surfaces of said arcuate sections 59 being approximately equal to twice the width W of the strip.

The strip material from which the blades are manufactured is preferably spring brass or Phosphor bronze, and tests indicate that it should have a thickness within the range of approximately .015 to .030 inch. Spring brass (such as commercially available Scoville alloy 23) having a thickness of .020 inch is particularly satisfactory. The two halves of the strip are bent back on each other along a smooth radius. When a spring brass material having a thickness of .020 inch is used this radius should be not less than about one-half the thickness of the strip. The two halves of the blade are symmetrically disposed with reference to the longitudinal axis of the blade, and the relative dimensions of the plug body and the shank portion S should be such that the inner or shank end of the bowed contact portion B normally will be spaced outwardly from the face of the plug body a distance about equal to once or twice the thickness of the strip of material from which the blade prong is made.

The proportions of the contact portions of the blades are such that the mid-point of the bowed contact portion B and the center lines of the defining arcuate surfaces for the two body sections 59 making up the contact portion B are spaced from the face of the plug body a distance approximately equal to or slightly less than the width W of the strip. This dimension is considered quite important in that it locates the widest part of the contact portion B so as to assure the obtaining of a good mechanical connection with the receptacle body. This will be described in greater detail in a subsequent paragraph. The blade should have a maximum transverse width in the body contact portion B, the dimension C in the drawings, approximately equal to one-half the width W of the strip from which the blade is made.

Particularly satisfactory results are obtained when the shank portion S of the spring blade of the present invention is provided with a longitudinally extending stiffening rib, as illustrated at 61 in the embodiment of Figs. 1 to 9. The

stiffening rib, if used, should preferably terminate adjacent the inner end of the bowed contact portion B, although as will hereinafter appear, certain other variations are possible with advantageous results. For example, if the stiffening rib is terminated short of the bowed contact portion B, a distance equal to about one-half of the width W of the strip, as illustrated at 63 in the embodiment of Figs. 27 and 28, there will be provided an auxiliary, straight, parallel sided, spring portion D adjacent the bowed contact portion B which will extend into the plug body for some distance.

The shank stiffening ribs are most conveniently formed by a rolling, stamping, or other embossing operation, and give good results when of a depth approximately equal to one-half the thickness of the strip material from which the blade is made. The stiffening ribs are preferably located centrally of the prong shanks, and a width of approximately one-half the width of the blade is satisfactory in most instances. In the different embodiments of the invention illustrated in the drawings, the stiffening ribs are of different lengths to accomplish certain different desired results.

In the construction illustrated in Figs. 1 to 9 inclusive, the ribs 61 terminate short of the lower ends of the two halves 65 and 67 of the blade shank S, and the lower end 69 of the inner half section 67 of the shank is folded over as illustrated particularly in Fig. 9. This folded over end 69 serves to hold the two half sections of the shank portion of the blade in contact with each other, and it is also used as a means for locking the blades in the blade supporting recesses 37 formed in the plug body. To facilitate the accomplishing of this locking function, the folded over end portion 69 should project outwardly from the plane of the blade; an angle of the order of 12 degrees as shown at M in Fig. 9 will usually function satisfactorily. This outwardly projecting, integral portion of the blade formed by the folded over end 69 is adapted to abut against the upper defining wall 38 of the blade receiving recess 37 formed in the outer body part 31, and thereby provides a highly effective means for locking the blades against longitudinal movement with reference to the plug body in which they are supported. The projection 73 which results from the termination of the rib 61 in the shank portion 65 short of the end thereof provides a spring abutment against which the folded over portion 69 of the other half 67 of the shank may rest. This is of value in facilitating the assembling of the device and in maintaining the folded over locking portion 69 in position.

The stiffening rib may be omitted in either or both of the shank sections. In such instances the half sections of the shank will be plain, as illustrated particularly in Fig. 25. These plain shank constructions are somewhat less satisfactory than the constructions which include a stiffening rib or ribs in one or both of the shank sections.

To provide an interlocking engagement with the stationary contacts 75 of the usual standard receptacles, such as are illustrated in Figs. 3 to 6, the two blade sections 57 which define the parallel sided contact portion A are preferably provided with opposed holes 77 which engage the usual projections 79 constituting a part of the receptacle contacts 75. The holes 77 may be formed by a straight punching operation, or by a combined punching and embossing opera-

tion. The holes 77 shown in the embodiment of the invention illustrated in Figs. 1 to 9 and also in the embodiments illustrated in Figs. 10 to 18 and 25 to 28 are of the straight punched type. Examples of the embossed type are illustrated at 81, in Figs. 19 to 24.

Aligning holes 83 are also punched or otherwise formed in the two half sections 65 and 67 of the blade shank for receiving the cord conductors so as to facilitate the soldering of the cord conductors to the blades. If desired, the holes 83 may be threaded as indicated in Figs. 27 and 28 for the reception of screw fastening means in place of the soldered connection 47 illustrated in the other figures of the drawing. The soldered connection 47 serves as an additional means for mechanically connecting the shank sections 65 and 67 of the blade construction illustrated in Figs. 1 through 9, and thereby stiffens the shank to some extent. In certain of the other illustrated embodiments of the invention, as for example, the construction illustrated in Figs. 19 through 26, the soldered connection 47 is relied upon as the principal means for fastening together the two half sections of the prong shank.

The improved operation of the spring blades of the present invention is illustrated particularly in Figs. 3, 4, 5, and 6. As shown in Fig. 3, the flat sided contact portion A and the curved outer end of the blades facilitates the entry of the blades into the blade receiving openings 85 in the insulating body 55 of the receptacle, and aid in effecting smooth operation of the bowed contact portions B as the plug is pushed into the receptacle. If the receptacle is of average construction and is provided with blade receiving openings 85 recessed about the average distance below the face of the receptacle, as illustrated in Figs. 3 and 5, by the time the blades are fully seated in the receptacle, the bowed contact portions B will have expanded so as to engage the inner edges of the sides of the blade receiving openings in the receptacle body as shown in Fig. 4. The plug and the blades will thereby be urged into the receptacle body. At the same time, each of the flat sided contact portions A, by virtue of the resilience of those portions of the blade and also by virtue of the resilient action of the bowed portions B, will engage and be held in firm contact with the cooperating receptacle contacts 75.

The net result is two-fold. By virtue of the engagement of the bowed contact portions B with the body 55 of the receptacle, the connector plug is mechanically connected to the receptacle body, while inside the receptacle a positive pressure electrical contact is assured. The mechanical connecting of the blade to the receptacle body prevents wobbling of the plug with the usual accompanying injury to the receptacle contacts, and the balanced spring action of the contact portions of the blades not only assures that the blades remain parallel as they are moved into and out of the receptacle, but in addition, assures positive electrical contact between the blades and the receptacle contacts when the blades are within the receptacle.

These advantages of mechanical connection between the plug body and the receptacle body and an improved spring pressure contact between the blades of the plug and the receptacle contacts are obtained with practically all of the "standard" receptacles now on the market. If the receptacle body is of the flush type, such as is shown in Fig. 5, the mechanical connection is

obtained some what farther down on the blades than is the case with the usual receptacle construction illustrated in Figs. 3 and 4.

In the extreme case of a receptacle body having very deeply recessed openings 85 for the plug contacts as illustrated in Fig. 6, the mechanical connection is attained adjacent or just below the mid-point of the bowed section B of the blade contacts. In this instance, the increased compression of the bowed contact portions B compensates for the somewhat lessened mechanical advantage of the connection and assures a positive mechanical inter-connecting of the receptacle body and the blade terminals of the plugs. The receptacle structures illustrated in Figs. 5 and 6 are extreme cases, but even in these instances it will be seen that the important advantages of the blade construction of the present invention are completely realized. None of the prior art arrangements has produced nearly as satisfactory operation as this.

While the embodiment of the invention just described has particular advantages, there are other possible blade constructions embodying the disclosed principles which will be found particularly useful under certain conditions. For example, in the small, flat-body plugs of the type illustrated in Figs. 10 and 11, the walls of the outer body part 31 are somewhat thinner and somewhat more flexible than is the case in the round type of plug illustrated in Figs. 1 and 2, and it is considered inadvisable to locate the blade locking means adjacent the base of the blade receiving recesses 37 in these plugs. Hence, the shank portions S of the prong construction shown in Figs. 12 to 18 are designed with a view to locking with an abutment 87 provided internally of the plug body by suitable extension of the recess 49 which serves the additional function of providing space for the soldered connection 47 used in connecting the cord conductors to the prongs. The contact portions A and B of the blades illustrated in these figures of the drawings are substantially identical in form and dimensions with the construction previously described, and the blades are manufactured in a similar manner by folding over and shaping a strip of suitable spring material of standard width.

In the particular prong construction shown in Figs. 10 to 14, the two half sections 89 and 91 of the shank portion S are provided with embossed ribs 93 which extend downwardly from the bowed contact portion B about one-third the length of the shank, the remainder of the half sections of the shank being flat. The end 95 of the outer shank section 91 is folded back upon itself as shown, to provide an integral, outwardly projecting latching portion 97. Suitable aligning openings 99 are punched through the two shank portions 89 and 91 and the folded over end 95 in order to receive the associated cord conductor which, in the assembled plug, will be soldered in place as shown particularly by the soldered connection 47 in Figs. 10 and 11. The soldered connection 47 also serves to mechanically connect the two half sections 89 and 91 of the shank portion and the folded over end 95.

This blade construction, as previously stated, is particularly adapted for use with soft body plugs of the flat shape shown in Figs. 10 and 11 but it will be apparent that blades of this type can be used in connection with plug bodies of other types and shapes. When used, the blades

are assembled in exactly the same manner as the blade construction previously described.

The blade construction shown in Figs. 15 to 18 is somewhat similar to the blade construction shown in Figs. 12 to 14, and is likewise particularly adapted for use in connection with the small, flat-sided, soft body plugs, although it is capable of use in connection with plug bodies of other types. The blade construction of Figs. 15 to 18 is likewise manufactured from a single, folded over strip of spring brass or other suitable material, and it includes an outer contact portion A and a second contact portion B, both of which are similar in form and dimensions to the contact portions A and B of the previously described constructions.

The shank portion S of this blade construction includes two cooperating sections 101 and 103 each of which is provided with a longitudinal extending, centrally disposed, stiffening rib 105. The ribs 105 have a width about equal to about one-half the width of the blade. The lower end of the inner shank section 101 is folded back as illustrated at 107, and the lower end of the outer shank section 103 is bent so as to provide an integral, outwardly extending projection 109 which is generally similar in function to the projection 97 of the construction previously described. Aligning holes 111 are punched in the folded over portion sections 101 and 107 to provide an opening for receiving the cord conductor to which the prong is attached in use.

The blade constructions illustrated in Figs. 19 to 28 are substantially identical with the blade constructions shown in my prior application, Ser. No. 375,870 of which this application is a continuation in part. In all of these constructions the blade is manufactured by folding over a strip of suitable material, such as spring brass, to provide two longitudinally spaced, transversely resilient, contact portions A and B which are substantially identical in shape and dimensions with the contact portions A and B of the previously described embodiments.

The shank portion S of the construction shown in Figs. 19, 20, and 22, is defined by two, parallel sections 113 of the strip from which the blade is manufactured. The shank sections 113 extend side by side in contact with each other, and particularly satisfactory results are obtained if the two shank portions 113 are provided with longitudinally extending stiffening ribs 115, as illustrated. The ribs 115 are conveniently formed, as in the previously described embodiments, by a rolling, stamping or embossing operation, and they may be of any convenient depth, although a depth of about one-half the thickness of the blade is particularly recommended. The ribs 115 should be centrally located and appear to give the best results with a width of approximately one-half the width of the blade. The rib 115 may be omitted in one or both of the shank sections 113 in which case that section of the shank will have the same appearance as the blade illustrated in Fig. 25. Aligned punched holes 119 are provided for reception of the associated conductor which may conveniently be soldered in place by a soldered connection 47, shown in Fig. 24. The soldered connection 47 serves the further function of mechanically joining together the two shank portions of the blade.

When using blades of the general type shown in Figs. 19, 20, and 22, there will be in some instances sufficient friction between the blades and the cooperating body parts of the plug to hold the

blades against lengthwise movement relative to the body when the plug is pushed into or withdrawn from the receptacle. However, as previously pointed out, positive interlocking of the blades with the plug body is sometimes desirable, and this blade construction can be readily changed to a locking type blade by the provision of a pressed out portion 117, as illustrated in Figs. 21 and 23, or other integral projection for engaging the plug body so as to anchor the blade therein. The pressed out portion 117 may conveniently constitute metal removed from one of the shank portions 113 to provide the conductor receiving hole 119.

In the specific construction illustrated, the pressed out portion 117 will engage the underside of the inner body part 39 as shown at the right hand side of Fig. 24. The other blade of the plug illustrated in Fig. 24 is of the same construction as the blade of Figs. 19, 20 and 22. It will be understood that under normal practice, both blades will be alike, and differing constructions have been illustrated in this single figure solely to simplify the drawings.

The blade construction illustrated in Figs. 25 and 26 is, as has been previously described, similar to the blade constructions of Figs. 19, 20, and 21 except that the shank portions 113 of the blade are not provided with a rib. This blade construction may advantageously include the integral locking projection 117 as shown particularly in Fig. 26.

The blade construction illustrated in Figs. 27 and 28 includes contact portions A and B, similar to the previously described embodiments, and also a spring portion D which, as previously described, is provided by terminating the stiffening ribs 63 short of the contact portion B. This construction further differs from the other embodiments of the invention in that the lower half of the shank section 121 is cut off so as to produce a shank portion which is in part of single ply construction. This is of value in certain instances, particularly where it is desired to save metal.

It will be apparent to those skilled in the art that various blade constructions embodying the principles described above may be devised. For this reason, it is my desire that the accompanying claims shall be accorded the broadest possible construction consistent with the language appearing therein and the prior art.

I claim:

1. A two ply, spring blade for electrical plug connectors and the like, comprising a flat, metal strip of standard blade width which is folded upon itself at the outer end of said blade and shaped to provide a flattened, transversely resilient, contact portion, a bowed, transversely resilient, contact portion, and a shank portion; said flattened contact portion being located at the outer end of said blade, comprising, coextensive, substantially parallel sections of said strip, which are spaced a short distance from each other, and having a length at least approximately equal to the width of said strip; said bowed contact portion being located longitudinally adjacent said flattened contact portion, having a length approximately one and one-half times the width of said strip, and comprising symmetrically opposed, outwardly bowed sections of said strip; said shank portion comprising coextensive, parallel sections of said strip which contact each other, and at least one of the parallel portions of said strip which constitute said

shank portion being provided with an embossed stiffening rib which extends longitudinally therewith for a substantial distance.

2. A two ply, spring blade for electrical plug connectors and the like comprising a flat, metal strip of uniform width which is folded upon itself at the outer end of said blade and is shaped to provide a flattened, transversely resilient, first contact portion, a bowed, transversely resilient, second contact portion, and a shank portion; said flattened contact portion being located at the outer end of said blade, comprising co-extensive, substantially parallel sections of said strip which are spaced apart a distance equal to about one-fourth the width of said strip, and having a length at least approximately equal to the width of said strip; said bowed second contact portion being located longitudinally adjacent said flattened contact portion, having a length approximately one and a half times the width of said strip and comprising symmetrically opposed sections of said strip which are curved along a circular arc, the radius of the defining surfaces of said arcuate curved sections being approximately equal to twice the width of said strip; said shank portion comprising coextensive parallel sections of said strip which contact each other, and at least one of the parallel portions of said strip which constitute said shank portion being provided with an embossed stiffening rib which extends longitudinally therewith for a substantial distance.

3. A two ply, spring blade for electrical plug connectors and the like, comprising a flat, metal strip of uniform width which is folded upon itself at the outer end of said blade and shaped to provide two, longitudinally spaced, two ply, transversely resilient contact portions, a transversely resilient spring portion, and a shank portion; one of said contact portions being located at the outer end of said blade and comprising coextensive, substantially parallel sections of said strip which are spaced a short distance from each other, the other of said contact portions being located longitudinally adjacent said first mentioned contact portion and comprising coextensive sections of said strip which are spaced apart a substantially greater distance than said parallel sections, whereby said other contact portion has a substantially greater maximum transverse width than said first mentioned contact portion; said spring portion comprising coextensive, spaced sections of said strip and being located intermediate said other contact portion and said shank portion.

4. A two ply, spring blade for electrical plug connectors and the like, comprising a flat, metal strip of uniform width which is folded upon itself at the outer end of said blade and shaped to provide two transversely resilient, contact portions, a transverse spring portion, and a transversely non-resilient, shank portion; one of said contact portions being located at the outer end of said blade and comprising coextensive, spaced, substantially parallel sections of said strip; the other of said contact portions being located longitudinally adjacent said first mentioned contact portion and comprising symmetrically opposed, outwardly bowed sections of said strip; said spring portion comprising coextensive, spaced, parallel sections of said strip and being located intermediate said last mentioned contact portion and said shank portion.

5. A two ply, spring blade for electrical plug connectors and the like, comprising a flat, metal

strip of uniform width which is folded upon itself at the outer end of said blade and is shaped to provide two, transversely resilient, two ply, contact portions, a transversely resilient, two ply, spring portion, and a transversely non-resilient, shank portion; one of said contact portions being located at the outer end of said blade, and comprising coextensive, spaced, substantially parallel sections of said strip; the other of said contact portions being located longitudinally adjacent said first mentioned contact portion and comprising symmetrically opposed, outwardly bowed sections of said strip; said spring portion comprising coextensive, spaced, parallel sections of said strip and being located intermediate said last mentioned contact portion and said shank portion; said shank portion comprising parallel sections of said strip which contact each other, and at least one of the parallel sections of said strip which constitute said shank portion being provided with an embossed stiffening rib which extends longitudinally therewith for a substantial distance.

6. A two ply, spring blade for electrical plug connectors and the like, comprising a flat, metal strip of uniform width which is folded upon itself at the outer end of said blade and shaped to provide two, transversely resilient contact portions and a transversely non-resilient shank portion; one of said contact portions being located at the outer end of said blade and comprising coextensive, substantially parallel sections of said strip which are spaced a short distance from each other; the other of said contact portions being located longitudinally adjacent said first mentioned contact portion and comprising coextensive sections of said strip, at least one of which is outwardly bowed so as to cause said other contact portion to have a substantially greater, maximum transverse width than said first mentioned contact portion; said shank portion comprising coextensive parallel sections of said strip and one of said sections being folded over so as to hold together the two parallel sections of said strip and to provide an outwardly extending projection which is adapted to engage and lock with the body of the plug with which said blade is used.

7. A two ply, spring blade for electrical plug connectors and the like, comprising a flat, metal strip of standard blade width which is folded upon itself at the outer end of said blade and shaped to provide a flattened, transversely resilient, contact portion, a bowed, transversely resilient, contact portion, and a shank portion; said flattened contact portion being located at the outer end of said blade and comprising coextensive, substantially parallel sections of said strip which are spaced a short distance from each other; said bowed contact portion being located longitudinally adjacent said flattened contact portion and comprising symmetrically opposed, outwardly bowed sections of said strip; said shank portion comprising parallel sections of said strip at least one of which is provided with a centrally located longitudinally extending stiffening rib, the end of one of the parallel sections of said strip being folded over the other section so as to mechanically interconnect the two sections of said shank portion and to provide an outwardly extending projection which is adapted to engage the body of the plug with which said blade is used to lock said blade against longitudinal movement relative thereto.

8. A two ply spring blade for electrical plug connectors and the like, comprising a flat metal

strip of uniform width which is folded upon itself at the outer end of said blade and shaped to provide two, transversely resilient, contact portions and a transversely non-resilient, shank portion; one of said contact portions being located at the outer end of said blade and comprising coextensive, substantially parallel sections of said strip which are spaced a short distance from each other; the other of said contact portions being located longitudinally adjacent said first-mentioned contact portions and comprising co-extensive sections of said strip which are spaced apart a substantially greater distance than said parallel sections, whereby said other contact portion has a substantially greater, maximum transverse width than said first-mentioned contact portion; said shank portion comprising parallel sections of said strip, at least one of said shank sections being provided with a longitudinally extending stiffening rib.

9. A two-ply spring blade for electrical plug connectors and the like, comprising a flat, metal strip of uniform width which is folded upon itself at the outer end of said blade and shaped to provide two, longitudinally spaced, two-ply, resilient contact portions and a shank portion, one of said contact portions being located at the outer end of said blade and comprising coextensive, substantially parallel sections of said strip which are spaced a short distance from each other, the other of said contact portions being located longitudinally adjacent said first-mentioned contact portion and comprising co-extensive sections of said strip which are spaced apart a substantially greater distance than said parallel sections, whereby said other contact portion has a substantially greater, maximum transverse width than said first-mentioned contact portion, and said shank portion comprising parallel sections of said strip which are fastened together by means which comprises an integral, formed part of one of said parallel sections.

10. A two-ply, spring blade for electrical plug connectors and the like, comprising a flat, metal strip of uniform width which is folded upon itself at the outer end of said blade and shaped to provide two, longitudinally-spaced, two-ply, resilient contact portions and a shank portion, one of said contact portions being located at the outer end of said blade and comprising co-extensive, substantially parallel sections of said strip which are spaced a short distance from each other, the other of said contact portions being located longitudinally adjacent said first-mentioned contact portion and comprising co-extensive sections of said strip, at least one of which is outwardly bowed so as to cause said other contact portion to have a substantially greater maximum, transverse width than said first-mentioned contact portion, said shank portion comprising parallel sections of said strip, which are in contact with each other and which are fastened together by means which comprises an integral, formed part of one of said parallel sections, said contact portions and said shank portions being in substantially straight line alignment with each other.

HUGO H. WERMINE.
